UNITED STATES PATENT OFFICE.

DELBERT W. CUSHMAN, OF FREMONT, OHIO.

CANOPY FOR TRACTORS.

Application filed May 18, 1927. Serial No. 192,322.

This invention relates to a canopy adapted primarily for use on tractors, one of the objects of the invention being to provide a light, durable and efficient device of this character 5 which can be mounted readily on a tractor and does not require the services of a skilled mechanic in order to place the same on or remove it from the tractor.

A further object is to provide a canopy 10 which will be supported firmly against displacement in any direction after once being applied and will afford ample protection from the sun and rain for the driver.

With the foregoing and other objects in 15 view which will appear as the description proceeds, the invention resides in the combination and arrangement of parts and in the details of construction hereinafter described and claimed, it being understood that changes 20 in the precise embodiment of the invention herein disclosed may be made within the scope of what is claimed, without departing from the spirit of the invention.

In the accompanying drawings the preferred form of the invention has been shown. 25

In said drawings,

Figure 1 is a perspective view of the canopy, the same being shown in position on a tractor, a part of which has been illustrated.

30 Figure 2 is an enlarged transverse section through one of the fenders showing one of the standards of the canopy connected thereto.

Figure 3 is a transverse section on an enlarged scale through one of the fenders or 35 guards showing another standard connected thereto.

Referring to the figures by characters of reference 1 designates a canopy having a frame of any suitable construction and extending downwardly from the front corners of this canopy are standards 2 each of 40 which is formed of parallel metal strips detachably connected by bolts 3. The lower ends of the strips constituting the standards 45 are bent in opposite directions to provide arms 4 and 5 adapted to rest flat upon the guard or fender A of the tractor, these arms being so shaped as to rest snugly on said guard or fender and being provided at their 50 free ends with hooks 6 downwardly and inwardly bent as shown for engaging the side edges of the guard or fender. Obviously by placing these hooks in engagement with opposed portions of the guard or fender and 55 then drawing the strips of the standard 2 together by means of the bolts 3, said guard or

fender will be firmly gripped and the standard held against displacement relative thereto. A similar standard 7 is extended from each of the rear corners of the canopy frame 60 but these rear standards are provided with downwardly and laterally inclined braces 8 each of which is held to its standard by one of the bolts 9 while the lower end of each plate is bolted or otherwise attached to one 65 of the outwardly extending arms 10 as shown at 11 in Figure 3. These braces tend to prevent the back portion of the canopy from sagging or swaying laterally. Downwardly and forwardly inclined bracing 70 strips 12 are connected to the front corner portions of the canopy frame and are adapted to be bolted or otherwise connected to the front portion of the tractor as shown at 13. If the bracing strips are attached as shown 75 in Figure 1, the bolts 13 employed for fastening them in place, are bolts commonly found on a tractor of a well-known type at the points where the attachments are to be made.

Obviously by providing a structure such 80 as described the same can be readily applied to or removed from position and when once placed will be held securely and rigidly and at the same time afford ample protection for the driver.

What is claimed is:

1. A canopy support for tractors and the like including separate strips arranged side by side, arms extending in opposite directions from the respective strips at their lower ends, hooks at the free ends of the arms, and means connecting the strips for drawing them together thereby to bind the hooks upon an interposed support on which the arms are adapted to be mounted.

2. The combination with opposed fenders of a tractor or the like, of a canopy support including a pair of standards above each fender, each standard including separate strips arranged side by side, oppositely extending arms at the lower ends of the respective strips, hooks at the free ends of the arms for embracing the adjacent edges of the fender, said arms being adapted to rest on the fender and support the standards, and means for drawing the strips together thereby to bind the hooks upon the adjacent edges of the fender to hold the standard against movement relative to the fender.

In testimony that I claim the foregoing as my own, I have hereto affixed my signature.

DELBERT W. CUSHMAN.
